UNITED STATES PATENT OFFICE.

FREDERICK C. WARNE, OF MANSFIELD, OHIO, ASSIGNOR TO RODERICK LEAN MANUFACTURING COMPANY, OF MANSFIELD, OHIO, A CORPORATION OF NEW JERSEY.

CULTIVATOR.

1,327,413.

Specification of Letters Patent.

Patented Jan. 6, 1920.

Application filed December 5, 1914. Serial No. 875,570.

To all whom it may concern:

Be it known that I, FREDERICK C. WARNE, a citizen of the United States, residing at Mansfield, in the county of Richland and 5 State of Ohio, have invented certain new and useful Improvements in Cultivators, of which the following is a specification.

My invention relates to improvements in cultivators, the present improvements being 10 particularly designed and adapted for use in connection with a wheeled cultivator, the present embodiment of the invention including a riding cultivator, of the "pivot axle" type provided with pivoted cultivator gangs.

15 The primary object of the invention is to provide an improved wheeled cultivator embodying and harmoniously combining all of the essential principles of operation and features of construction of the ordinary riding 20 pivot axle and pivot gang cultivators.

A further object is the provision of an improved cultivator having means whereby the supporting or ground wheels and cultivator gangs may be simultaneously and correspondingly tilted or swung laterally through 25 the single or simultaneous lateral swinging movement or actuation of said gangs to one side or in the same general direction, or the gangs be moved uniformly toward or from 30 each other without imparting any tilting or lateral movement to said ground or supporting wheels on their pivots. In other words, suitable means or mechanism is interposed between and connected to the pivoted gangs

35 and cultivator or supporting wheels whereby when the gangs are simultaneously swung laterally by the operator in the same direction or to one side through the foot stirrups or the handles, such movement will correspondingly move or actuate the supporting 40 wheels whereby to carry the cultivator frame in the same general direction, or when one of said gangs is moved laterally and independently without the concurrence of the 45 other, said supporting wheels will be correspondingly moved proportionately or to what may be termed a "half-cut," that is to say, a movement of substantially half of the movement occasioned when both of said 50 gangs are moved in the same direction as above indicated.

A still further object is the provision of improved wheel and gang connecting, actuating, and controlling mechanism, in the

present instance, in the form of what may be 55 termed a "compensating or equalizing yoke" adapted not only to simultaneously and correspondingly swing or pivot the cultivator or supporting wheels through the single or simultaneous lateral swinging movements 60 of said gangs as above described, but which will stand neutral or out of action with respect to said supporting wheels when the gangs are moved uniformly and simultaneously toward or from each other. 65

A still further object is the provision, or combination with a cultivator of the general character above indicated, of an improved coöperating seat carrying lever pivotally mounted above and extending longitudinally of the cultivator frame, the forward end of said seat lever carrying a pivotally mounted cross or equalizing bar the ends of the latter being provided with suitable depending connecting members or links 70 detachably and adjustably connected to the cultivator beams or gangs at the rear of their pivoted connection with the cultivator arch or frame, said seat lever being also provided with means for shifting its pivot or 75 fulcrum, it being obvious that this shifting of the pivot or fulcrum point of the seat lever, or of the point of link attachment to the cultivator beams or gangs, furnishes two alternate means for adjusting the mechanism to suit the weight of the operator. Under normal conditions the weight of the operator in the seat overbalances the cultivator gangs and the teeth or shovels thereof are 80 out of and clear from the ground so as to permit of idle transportation and corner turning of the implement without any further attention, and when it is desired to bring the gangs into action, the operator simply exerts a sufficient downward pressure 85 upon the plow handles or stirrups, or both, to keep the cultivator teeth or shovels to their work, making such up and down and side or lateral adjustments or movements (including under certain desired conditions the 90 harmonious swinging of the cultivator or ground wheels) as the constantly changing working conditions call for, such counterbalancing seat lever, in combination with the mechanism hereinbefore described, giving 95 the operator perfect control of the cultivator gangs both vertically and horizontally as well as independently of each other and of 100 105

the cultivator wheels under counterbalanced conditions, calling upon him for the exertion of but little strength in meeting the various exigencies of actual service.

5 With the above mentioned and other ends in view, the invention consists in the novel construction, arrangement, and combination of parts, hereinafter described, illustrated in one of its embodiments in the accompanying 10 drawings, and particularly pointed out in the appended claims.

Referring to the drawings, forming a part of this specification, Figure 1, is a front perspective view of a wheeled cultivator embodying my invention, in its normal or operative position, the shovels being removed and the cultivator gangs and pivot wheels extending in parallel relation to each other (see diagrammatic view, Fig. 12).

20 Fig. 2, a rear perspective view of the same, the pivoted gangs and wheels being swung to their extreme left (see diagrammatic views, Figs. 13 and 14.)

25 Fig. 3, a rear perspective view of the same with the cultivator gangs elevated or put up in locked relation on the pivoted axle portions of the cultivator or ground wheels (see diagrammatic view, Fig. 18).

30 Fig. 4, an enlarged top plan view of the same with the pivoted gangs and wheels in normal or parallel relation to each other (see diagrammatic view, Fig. 12).

35 Fig. 5, a side elevation of the same, one of the wheels and some of the brace members being removed for the purpose of clearer illustration of the parts.

40 Fig. 6, an enlarged front elevation of the cultivator wheel and pivot gang connecting, actuating, and controlling device, in the present instance, in the form of a two-part geared compensating or equalizing yoke, the dotted lines designating the extreme positions of the gang and yoke members when moved simultaneously and uniformly toward and from each other.

45 Fig. 7, a fragmentary top plan view of the bearing and geared portions of the improved device or yoke.

Fig. 8, a detail top plan view of one of the yoke arm receiving and containing keeper clips or members carried at the forward or pivoted ends of the gang beams.

50 Fig. 9, an enlarged rear view of one of the pivot wheel axles, the dotted lines representing the manner in which the cultivator gangs may be put up in locked relation therewith for ordinary transportation on the cultivator wheels.

55 Fig. 10, a fragmentary front view of the upper portion of the pivot wheel axle sleeve.

Fig. 11, a diagrammatic view of the cultivator wheel and pivot gang connecting and controlling device, in the present instance, in the form of a yoke, the arrow and dotted line positions illustrating the manner in

which the device or yoke is moved to pivot the wheels (see Fig. 15) when the cultivator gangs are moved simultaneously to the right.

Fig. 12, a diagrammatic view showing the position of the pivoted wheels and gangs 70 when in normal or parallel relation to each other.

Fig. 13, a view similar to Fig. 11 showing the position of the parts when moved to the left. 75

Fig. 14, a diagrammatic view showing the position of the parts and the cultivator gangs when simultaneously moved to the extreme left as illustrated in Figs. 2 and 13 of the drawings. 80

Fig. 15, a similar view showing the position of the parts when the cultivator gangs are moved to the extreme right.

Fig. 16, a similar view illustrating the neutral position of the pivot gang connecting 85 and controlling device or yoke with respect to the cultivator wheels when the gangs are simultaneously and uniformly moved toward each other to their extreme inner position. 90

Fig. 17, a similar view showing the position of the parts, or the "half-cut" position of the wheels when the left gang only is moved to its extreme left without the movement or concurrence of the right gang. 95

Fig. 18, a similar view showing the neutral position of the yoke or pivot gang connecting and controlling device with respect to the wheels when the gangs are simultaneously moved outwardly from each other, or when in their extreme outer or put up position in locking engagement with the pivot wheels as illustrated in Fig. 3 of the drawings. 100

Similar numerals of reference designate 105 like parts throughout all the figures of the drawings.

The improved cultivator comprises a suitable frame consisting, in the present instance, of a pair of side members 1, converging at their front ends and bolted to the tongue 2, the rear ends being bolted to the axle beams 3. 110

The rear end of the tongue 2, and forward portions of the frame members 1, are 115 provided with a depending gang arch 4, and the axle beams 3, are provided with sleeves 3^a, adapted to receive and adjustably contain the stub axles 5. The vertically extending portions of the stub axles are 120 provided with axle bearing pivot sleeve 6, the latter being provided on their outer sides with the cultivator wheel axles 6^a, and on their inner sides with bracket members 6^b, the latter being adapted to receive and support 125 the pivoted cultivator gangs 7, when the latter are elevated or put up for transportation as illustrated in Fig. 3 of the drawings, it being obvious that when the gangs 7, are thus hooked upon the bracket 130

members 6^b, the cultivator wheel axle 6^a, and the cultivator or ground wheels 8, will be further locked as against tilting or vibrative movements on the pivots in transportation.

As a means of securing the pivot sleeves 6, on the stub axles 5, as well as for limiting the pivotal movements of the sleeves the latter are provided with slots 6^c, (see Fig. 10) adapted to receive and contain stub bolts 5^a, and as a means of connecting and simultaneously actuating the pivot sleeves 6, said sleeves are provided with forwardly extending arms 9, connected to each other by means of links 10, said links 10, in the present instance, being connected to a laterally movable supporting member or spreader link 11.

The cultivator gangs 7, are pivoted for both vertical and lateral movements by means of coupling members 12, the latter being adjustably mounted toward and from each other, or horizontally, in coupling frames 12^a, at the lower ends of the gang arch 4.

The rear portions of the gangs are provided with suitable stirrups 13, and handles 14, by means of which the gangs may be given the desired movements as hereinafter described.

The improved cultivator wheel and gang connecting, actuating, and controlling mechanism whereby the supporting or ground wheels and pivoted cultivator gangs may be simultaneously and correspondingly tilted or swung laterally through the single or simultaneous lateral swinging movement or actuation of said gangs, or whereby the latter may be moved uniformly toward or from each other in the active cultivation in and along the row of growing plants, without imparting any tilting or lateral movement to said supporting wheels on their pivots comprises, in the present instance, what may be termed a "compensating or equalizing yoke" consisting of two lever members 15, pivotally mounted on the laterally movable member or spreader link 11, and connected or geared to each other intermediate their pivots in some suitable and convenient manner, as for example, by segmental gears or racks 15^a, the lower ends of said lever members extending beneath and being movably connected to the cultivator beams, in the present instance, through the medium of a keeper clip or bracket 7^a, whereby the requisite vertical and lateral movements may be given to the cultivator gangs by the operator without any interference with the movements of the connected parts. The yoke lever members 15, may be pivotally secured on the laterally movable supporting or spreader member 11, by means of pivot bolts 15^b, and if desired, the segmental gears 15^a, may be separately formed and adapted to the lever members 15, by means of attach-

ing bolts 15^c, as shown most clearly in Fig. 6 of the drawings. If desired, the lever members 15, may be secured in fixed relation to each other in some suitable and convenient manner, as for example, by means of a clamping bolt 16, extending through a slot 15^d, and one of the gears 15^a, in which instance it will be apparent that the members 15, will form a "gang spreader yoke" thereby preventing the gangs from being moved toward or from each other only permitting of the swinging or tilting movements of the ground wheels through the corresponding simultaneous lateral or swinging movements of the cultivator gangs.

By reason of the above construction it will be apparent that when the cultivator gangs are simultaneously and uniformly moved toward or from each other and the lever members 15, correspondingly moved as indicated by dotted lines in Fig. 6 of the drawings, that no lateral motion will be imparted to the supporting or spreader member 11, connected to the pivoted cultivator wheels through the links 10, and arms 9, the member 11, maintaining a neutral position with respect to the pivoting of said cultivator wheels, but that upon the simultaneous lateral movements of the gangs to the right or to the left as indicated in Figs. 11 and 13, respectively, said gangs will hold the lever members 15, in substantially uniform or constant spaced relation to each other as shown, thereby carrying the member 11, and its connections to the right or to the left and correspondingly moving the pivoted wheels to the right or to the left as indicated in Figs. 15 and 14, respectively.

As a further means of enabling the operator to retain complete control of each cultivator beam or gang independently of the other, moving it separately either vertically or horizontally, as required by the crop, or condition or contour of the surface, or in passing obstructions, as well as providing means for counterbalancing the weight of the cultivator gangs whereby to more completely and harmoniously actuate the gangs and their connections for the purposes hereinbefore mentioned, a seat carrying lever 17, is provided, said lever, in the present instance, comprising two beam members pivotally mounted above the arch or axle portion of the cultivator frame, in the present instance, by means of a curved plate 18, upon which the members of the seat carrying lever 17, are adapted to rock to form a movable fulcrum for the latter, the rear end of the seat lever being provided with a seat 19, for the operator, and the forward end of the lever being provided with a pivoted cross bar 20. The free or outer ends of the cross bar 20, are provided with depending links or connecting members 21, adapted to be hooked into a plurality of openings 7^b, of

- the cultivator gangs whereby the leverage exerted by the lever 17, upon the gangs may be adjusted to correspond with the weight of the operator in the seat 19, it being also apparent that the leverage may be still further regulated or adjusted by moving the lever 17, forwardly or rearwardly through the medium of the pivot bolt 22, and the openings 22^a.
10. From the foregoing description, taken in connection with the accompanying drawings, the operation and advantages of my invention will be readily understood.
- Having thus described one of the embodiments of my invention, what I claim and desire to secure by Letters Patent, is,—
1. In a cultivator, including laterally swinging wheels and gangs, a supporting member movably connected to said wheels, and lever members on said supporting member intercommunicating with each other for uniform relative movement by corresponding relative movement of said gangs.
  2. In a cultivator, a frame provided with laterally swinging pivot gangs and laterally swinging pivot wheels, a movable wheel guiding element, and lever members on said wheel guiding element intercommunicating with and uniformly movable relative to each other and so operated by said pivot gangs only when the latter are moved uniformly toward and from each other.
  3. In a cultivator having laterally swinging pivot wheels and gangs, wheel guiding and gang connecting elements movably interposed therebetween, said gang connecting elements being intergeared for a like movement toward each other through a like movement of said gangs independently of and while holding said wheel guiding element in a central or neutral position.
  4. In an agricultural machine, a frame provided with laterally swinging wheels and earth working implements, and wheel and implement connecting elements movably interposed therebetween, said implement connecting elements being intergeared to each other on said wheel connecting element for uniform relative movements to each other by like movements of said earth working implements without imparting any movement to said wheel connecting element.
  5. An agricultural machine, comprising a frame, laterally swinging guiding and earth working elements carried thereby, and laterally swinging connecting and controlling elements between said guiding and earth working elements, some of said connecting elements being intergeared to each other for uniform movement toward each other by like movement of said earth working elements without imparting any movement to said laterally swinging guiding element and holding the latter in a stationary position when so moved.
  6. In combination with a cultivator frame provided with laterally swinging wheels and gangs, a movable wheel connecting and guiding member, articulated gang actuated members mounted on and carried by said wheel connecting and guiding member, said articulated members intercommunicating with each other and holding said wheel connecting and guiding member in a neutral position when uniformly moved relatively but constructed and arranged to interlock in fixed relative and opposed relation to each other to simultaneously swing said wheel connecting and guiding member when moved by corresponding movements of said gangs.
  7. An agricultural machine, comprising a wheeled frame provided with laterally swinging guiding and earth working elements, and mechanism interposed between and connected to said guiding and earth working elements, said mechanism including movable articulated gang actuated elements carried by said guiding element for uniform movement toward each other by like movement of said gangs and as so moved holding said guiding element in a central position and interlocking with each other in opposing relation for concurrent lateral movement of said guiding element by like lateral movement of said gangs.
  8. An agricultural machine, comprising a wheeled frame provided with laterally swinging guiding and earth working elements, and laterally swinging gang actuated elements movably interposed between and connected to said guiding and earth working elements said gang actuated elements being movably articulated on said guiding element for uniform movement toward each other without movement of said guiding element and interlocking for concurrent lateral movement of said guiding element when correspondingly moved by a like movement of said earth working elements.
  9. An agricultural machine, comprising a frame, laterally swinging wheel guiding and earth working elements carried thereby, and connecting elements interposed therebetween, said elements being movably intergeared on said wheel guiding element whereby the same may be moved toward each other uniformly by a like movement of said earth working elements without imparting any movement to said laterally swinging wheel guiding element and whereby the same will be interlocked in opposing relation to each other for concurrent lateral movement of said wheel guiding element by a like movement of said gangs.
  10. An agricultural machine, comprising a frame, laterally swinging guiding and earth working elements carried thereby, and laterally movable connecting elements interposed therebetween some of said elements

- being movably interconnected on said guiding element and to said earth working elements whereby the same may be moved toward each other uniformly by a like movement of said earth working elements without imparting any movement to said laterally swinging guiding element and whereby the same will be interlocked with and for a concurrent lateral movement of said guiding element by a like movement of said gangs. 5
11. In combination with a cultivator provided with laterally swinging pivot wheels and gangs, laterally swinging wheel connecting and gang actuated elements movably interposed therebetween, said gang actuated elements being carried by and movable on said wheel connecting element and intergeared with each other for a like movement toward each other by like movements of said gangs while holding said wheel connecting element in a neutral or central position and interlocking in opposing relation to each other for a concurrent lateral movement of said wheel connecting element by a like concurring lateral movement of said gangs. 15
12. In an agricultural machine, a movable steering element, earth working elements, and intergeared elements movably connected to each other and to said steering and earth working elements and operable by the latter. 20
13. In a wheeled agricultural machine, laterally movable steering and implement elements carried thereby, and laterally movable elements intergeared to each other and movably connected to said steering and implement elements and operable from and by the latter. 25
14. In an agricultural machine, a vehicle frame, laterally movable steering and earth working elements therefor, and connecting and controlling elements movably intergeared with each other and with said steering and earth working elements and operable by the latter toward and from each other irrespective of said steering element and interlocking with each other and imparting movement to said steering element when otherwise moved by said earth working elements. 30
15. A cultivator steering and controlling device, comprising a laterally swinging steering member, and gang connecting gang actuated elements intergeared with each other and with said laterally swinging steering member for uniform relative movement toward and from each other and for holding said steering member in a neutral position when so moved, said intergeared elements being also constructed and arranged relatively interlocking and concurrently moving said steering member laterally when otherwise moved. 35
16. In an agricultural machine, the combination of steering means, freely movable implements, members movably connected to the steering means and to the implements, and connections between said members constructed to move the steering means when the implements are simultaneously moved in the same direction, and arranged for simultaneous like movement toward and from each other while retaining the steering means motionless. 40
17. An agricultural machine provided with pivot axles and wheels, a member pivotally connected to said axles, freely movable implements, elements movably connected to the member and to the implements, and connections between said elements constructed and arranged to permit the implements to be uniformly moved toward and from each other while retaining the member motionless, and imparting movement to said member when the implements are simultaneously moved in the same direction, or one held stationary and the other moved. 45
18. A cultivator provided with pivot axles and wheels, a radius bar pivotally connected to the axles, freely movable cultivator beams, members pivoted on the bar and movably connected to the beams, and connections between the members arranged to allow movement of the beams toward and from each other while retaining the bar motionless, and moving the bar when the beams are simultaneously moved in the same direction. 50

In testimony whereof I have affixed my 100
signature in presence of two witnesses.
